DESIGN FOR A SHOE

David S. Cohen, New York, N. Y.

Application November 24, 1942, Serial No. 108,860

Term of patent 3½ years

To all whom it may concern:

Be it known that I, David S. Cohen, a citizen of the United States of America, residing in New York city, county of New York, and State of New York, have invented a new, original, and ornamental Design for a Shoe, of which the following is a specification, reference being had to the accompanying drawing, forming part thereof.

Fig. 1 is a perspective view of a shoe showing my new design.

Fig. 2 is a bottom plan view thereof.

I claim:

The ornamental design for a shoe, substantially as shown.

DAVID S. COHEN.
